(57) **CLAIM**

The ornamental design for a delivery device for an air treatment composition, as shown and described.

DESCRIPTION

FIG. 1 is a top perspective view of the delivery device for an air treatment composition;

FIG. 2 is a front, elevation view thereof;

FIG. 3 is a rear, elevation view thereof;

FIG. 4 is a first side, elevation view thereof;

FIG. 5 is a second side, elevation view thereof;

FIG. 6 is a top, plan view thereof; and,

FIG. 7 is a bottom, plan view thereof.

Features illustrated in the various drawing figures which are depicted using broken-lines form no part of the claimed design.
